UNITED STATES PATENT OFFICE.

FRANK G. WALTZ, OF TOLEDO, OHIO, ASSIGNOR, BY MESNE ASSIGNMENTS, TO THE TOLEDO BUTTON MACHINE COMPANY, OF TOLEDO, OHIO, A CORPORATION OF OHIO.

BUTTON-PLACING FINGER-GUIDE FOR SHOE-BUTTON-FASTENING MACHINES.

1,206,957.

Specification of Letters Patent.

Patented Dec. 5, 1916.

Application filed January 14, 1916. Serial No. 72,060.

To all whom it may concern:

Be it known that I, FRANK G. WALTZ, a citizen of the United States, and a resident of Toledo, in the county of Lucas and State 5 of Ohio, have invented a certain new and useful Button-Placing Finger-Guide for Shoe-Button-Fastening Machines; and I do hereby declare the following to be a full, clear, and exact description of the invention, 10 such as will enable others skilled in the art to which it appertains to make and use the same, reference being had to the accompanying drawings, and to the characters of reference marked thereon, which form a 15 part of this specification.

This invention relates to shoe button fastening machines, and particularly to means for guiding the movements of the button placing finger thereof. In the use of machines of this character considerable difficulty has been experienced due to lateral play of the button placing finger permitting its free end to slip laterally from engagement with some buttons, if undersized or 20 of irregular form, thus preventing a regular successive feeding of the buttons to the stapling parts.

The object of my invention is the provision of simple and efficient means for 30 guiding the reciprocatory or button placing movements of placing fingers of machines of the class described, whereby to obviate the objections above noted and to insure a more perfect and satisfactory working of 35 the button placing means than has heretofore been obtained.

The invention is fully described in the following specification, and while, in its broader aspect, it is capable of embodiment 40 in numerous forms, a preferred embodiment thereof is illustrated in the accompanying drawings, in which,—

Figures 1 and 2 are side elevations of the portion of a shoe button fastening machine 45 embodying the invention, with the button placing finger in different positions of its movement, and Fig. 3 is a front elevation of Fig. 1, with parts removed.

Referring to the drawings, 1 designates 50 the frame of a shoe button fastening machine, and 2 the button delivery tube or chute thereof.

3 designates a rocker-arm which is pivoted to and rises above the frame 1 at one 55 side thereof for forward and backward rock-

ing movements, and has a stem or stub-shaft 4 fixedly projecting transversely from its upper or free end over the top of the frame 1.

The button placing finger 5 of the machine is mounted loosely on the outer end of the shaft 4 in spaced relation to the rocker-arm and projects forward and downward from the shaft in position for its lower or free end to engage a button 6 in the lower 60 end of the tube 2 and move it forward therefrom to staple receiving and setting positions when the arm 3 has forward rocking movements. The delivery end of the tube 2 is transversely offset toward the center 65 of the frame 1 from the vertical plane of the inner end of the placing finger 5, and it is therefore necessary to offset the outer end portion of the finger in the same direction from its inner end, as shown at 5^a. It is 70 thus evident that the free end of the placing finger 5 is transversely offset both from its inner end and from the rocker arm 3, thereby rendering it extremely difficult, if not impossible, to prevent lateral movements of 75 the free end of the placing finger which will permit it to slip from engagement with the top of a button 6 if undersized or not of proper shape on its top surface.

A coiled expansion spring 7 is mounted 80 on the stub-shaft 4 between the arm 3 and placing finger 5 and has its outward ends thrust thereagainst to retain them spaced and take up looseness therebetween. One 85 end of the spring 7 is anchored to the arm 3 and its other end is extended transversely 90 from the shaft and fixed to a tail-piece 8 on the finger 5, and serves to yieldingly retain the free end of the finger in its lowered 95 position.

The forward and backward movements of the placing finger 5 are guided by a guide-finger 9, which is fixed to the frame top at one side of the forward end portion of the button delivery tube 2 and extends upward 100 and forward on an incline therefrom. The upper or free end of the finger 9 is doubled over in inverted U-shape to form spaced guiding legs between which the forward end portion of the placing finger 5 is disposed 105 for sliding reciprocatory movements relative thereto. The guide finger 9 coacts with both sides of the finger 5 to prevent lateral movements thereof and to retain the free end of the finger in engagement with the 110

top of a button 6 during a forward button placing movement of the finger. The guide 9 is inclined so as to brace the placing finger 5 during its entire forward stroke and to 5 permit the finger 5 to be swung upward from within the guide when the placing finger is at the limit of its rearward stroke, as shown in Fig. 2, the free end of the finger 10 when in such position swinging in an arc 10 which is disposed immediately at the rear of the upper looped end of the guide finger.

Having thus described my invention, what I claim as new and desire to secure by Letters Patent, is,—

15 In a machine of the class described, a frame, a rocker-arm carried by said frame

and having a shaft projecting transversely from its free end, a finger carried by said shaft in transversely spaced relation to the rocker arm and for rocking movements relative thereto, the free end portion of said finger being transversely offset from its inner end portion, and a guide finger extending upward and forward from the frame and having its upper portion disposed in the 25 vertical plane of movement of the free end portion of said placing finger and doubled over to form a guide through which the free end portion of the placing finger projects.

In witness whereof, I have hereunto 30 signed my name to this specification.

FRANK G. WALTZ.
